UNITED STATES PATENT OFFICE

115,948

DESIGN FOR A TOOTH SHADE GUIDE UNIT

Glenn A. Barnes, Philadelphia, Pa., assignor to
Universal Dental Company, Philadelphia, Pa.,
a corporation of Pennsylvania

Application February 17, 1939, Serial No. 83,047

Term of patent 7 years

To all whom it may concern:

Be it known that I, Glenn A. Barnes, a citizen of the United States and a resident of Philadelphia, county of Philadelphia, State of Pennsylvania, have invented a new, original, and ornamental Design for a Tooth Shade Guide Unit, of which the following is a specification, reference being had to the accompanying drawing, forming a part thereof, wherein:

Fig. 1 is a perspective view of a tooth shade guide unit showing my new design;

Fig. 2 is an end elevational view thereof; and
Fig. 3 is a top plan view thereof.

I claim:

The ornamental design for a tooth shade guide unit, as shown.

GLENN A. BARNES,
